VEHICLE LIGHT

Harold L. Lester, Boscobel, Wis.

Application April 21, 1950, Serial No. 9,399

Term of patent 7 years

(Cl. D48—32)

To all whom it may concern:

Be it known that I, Harold L. Lester, a citizen of the United States, residing at Boscobel, in the county of Grant and State of Wisconsin, have invented a new, original, and ornamental Design for a Vehicle Light, of which the following is a specification; reference being had to the accompanying drawing forming a part hereof, in which:

Figure 1 is a front elevational view of a vehicle light, showing my new design;

Figure 2 is a top plan view; and

Figure 3 is an end elevational view.

I claim:

The ornamental design for a vehicle light, as shown.

HAROLD L. LESTER.
